Primary Examiner — Stella Reid*Assistant Examiner* — Elizabeth J Oswecki(74) *Attorney, Agent, or Firm* — Alan G. Towner(57) **CLAIM**

The ornamental design for a paste jar, as shown and described.

DESCRIPTION

FIG. 1 is a top isometric view of a paste jar showing our new design;

FIG. 2 is a bottom isometric view thereof;

FIG. 3 is a side view thereof;

FIG. 4 is a bottom view thereof; and,

FIG. 5 is a top view thereof.

The broken lines showings in FIGS. 1-3 and 5 are environmental only and not part of the claimed design.

1 Claim, 4 Drawing Sheets*FIG. 1*

FIG. 2

FIG. 3

FIG. 4

FIG. 5
